CLAIM

The ornamental design for a valve block, as shown and described.

DESCRIPTION

FIG. 1 shows a perspective view of a component of a valve. FIG. 2 shows another perspective view of the component of a valve.

FIG. 3 shows a front view of the component of a valve

FIG. 4 shows a rear view of the component of a valve

FIG. 5 shows a top view of the component of a valve

FIG. 6 shows a bottom view of the component of a valve

FIG. 7 shows a right side view of the component of a valve; and,

FIG. 8 shows a left side view of the component of a valve. The broken lines in the drawings are included for the purpose of illustrating portions of the valve block and form no part of the claimed design.
